UNITED STATES PATENT OFFICE.

THOMAS J. MCADAMS, OF ST. LOUIS, MISSOURI.

COMBINATION-TOOL.

1,324,509.

Specification of Letters Patent.

Patented Dec. 9, 1919.

Application filed October 7, 1918. Serial No. 257,125.

To all whom it may concern:

Be it known that I, THOMAS J. MCADAMS, a citizen of the United States, residing in the city of St. Louis and State of Missouri, have invented a new and useful Improvement in Combination-Tools, of which the following is a specification.

This invention relates to combination tools, and more particularly to a combined 10 ratchet brace and lifting jack. It has for its principal objects to produce a structure which is simple, and yet powerful and rapid in operation; to provide for the ready interchange and use of different attachments or 15 implements, such as drill, screw-driver or wrench-socket bits, etc.; and the quick change of the device from brace to lifting jack, and vice versa; and to attain certain advantages as will hereinafter more fully appear.

The invention consists in the novel construction, and in the parts and combinations and arrangements of parts hereinafter described and then set forth in the claims.

In the accompanying drawings illustrating a practical embodiment of the invention,

Figure 1 is a view in side elevation;

Fig. 2 is a longitudinal section;

Fig. 3 is a fragmentary section on the line 3—3 of Fig. 1;

Fig. 4 is a horizontal section on the line 4—4 of Fig. 2;

Fig. 5 is a similar view on the line 5—5 of Fig. 2;

Fig. 6 is a section of a socketed base for supporting the device as a lifting jack;

Fig. 7 is a detail view, partly in section, of a swiveled jack-table or shelf;

Fig. 8 is a diagram showing the relative arrangement of the ratchet-pins; and

Figs. 9 and 10 are detail views illustrating the application of a holding and feeding apparatus for drilling purposes.

Referring now to the drawing, the numeral 1 designates the handle or stock of the device, which may be made of hard wood or metal, as desired. Secured on the handle, as by a socket or ferrule portion 2, is a body or head, whose lower and upper portions 3, 4, respectively, are substantially cylindrical and coinciding axially with the handle 1, while an intermediate portion 5 is also substantially cylindrical, but with its axis crosswise.

In the body or head is an axial bore 6 through which a spindle or shaft 7 extends and is capable of both endwise and rotative movement therein; while in the handle or stock proper is a continuation 6^a of said bore 6, but preferably, though not necessarily, of slightly larger diameter. On the outer end of the spindle 7 is a head or collar 8 affording a thrust bearing with the bushing 9 which is screw-threaded into the end portion 4 of the body and held in place by a jam-nut 9^a.

Journaled in a loose, flanged bearing sleeve or bushing 10 in the recessed inner portion 11 of the bushing 9 is a beveled pinion 12 which has a key or spline 13 slidably fitting a longitudinal groove 14 in the spindle 7, whereby the latter is rotated with, but permitted to move endwise through, said pinion 12, said groove being shown by dotted lines in Fig. 2, but more clearly in Fig. 5.

The spindle 7 is screw-threaded from its inner end, as at 15, for a greater or lesser portion of its length; and adjacent to where the threads 15 terminate, it is provided with an annular groove 16.

Working transversely in the body portion 3 are two diametrically-opposed, reciprocatory clutch members or latch-pins 17 which are adapted to engage the groove 16 so as to swivel the spindle 7; that is, permit rotation of the spindle, but hold it from endwise movement during such engagement.

In the body portion 3, also, are two other, like opposed and movable, clutch members or blocks 18 having their meeting end portions concaved and screw-threaded correspondingly to the screw-threaded portion 15 of the spindle 7, so that, when engaged with the latter, and the members 17 are disengaged from the groove 16, the spindle is caused to travel endwise as it is rotated.

It is desirable to effect a simultaneous and relative inverse actuation or adjustment of the members 17 and 18. Therefore, a means is provided to move the one set inward while permitting the other set to move outward. As shown, the members 17 have beveled heads 17^a between which and the shoulders at the inner ends of enlargements of the slideways in which the members work, are interposed springs 19; while the members 18 have similar heads 18^a and the interposed springs 20.

Rotatable on the body portion 3 is a ring 21, preferably nubled or otherwise circumferentially formed or provided to facilitate its manipulation, and having apertures 22, corresponding to the heads 17^a, and additional apertures 23 for the heads 18^a, the one set of apertures being diametrically disposed in a different direction from the other set; that is, the arrangement is such that when the ring 21 is turned to bring the one set of apertures in position to receive the corresponding heads of the members 17 or 18, as the case may be, the other set of apertures is out of receiving position. Consequently, while the one set of clutch members 17 or 18 is in, the other is out of, engagement with the spindle 7.

The ends of the apertures 22 and 23 are beveled correspondingly to the bevel of the heads 17^a and 18^a, so as to readily engage the latter with cam effect as the sleeve 21 is turned, and thereby force the respective members 17 or 18 inward against the pressure of the springs 19 and 20, and into engaging relation to the spindle 7; and in which position they are maintained until the sleeve is turned to bring the respective apertures back to position to release said members (see Figs. 2, 4 and 5).

The sleeve 21 is further provided with additional apertures 22^a for the members 17, and likewise additional apertures 23^a for the members 18, said apertures 22^a and 23^a being so arranged and correlated as to permit both the members 17 and 18 to be released from engagement with the spindle 7 at the same time, whereby to permit the spindle to be readily withdrawn from, and returned to, the stock at will.

To hold the sleeve 21 in adjusted position and to permit it to be readily released to effect the adjustments of the members 17 and 18, as above noted, it is provided with a spring-pressed latch member 21^a having a pin or stud 21^b which operates through an aperture in the sleeve and engages in either one of three recesses 3^a, 3^b or 3^c provided therefor in the body portion 3 (see Fig. 5). By this arrangement, when the pin 21^b is in the recess 3^a, both the members 17 and 18 are out of engagement with the spindle 7, as in this position of the sleeve the apertures 22^a are brought to receiving position for the heads 17^a and the apertures 23^a to receiving position for the heads 18^a, and during which time the spindle is withdrawable and insertible through the bores 6 and 6^a of the stock, as just above pointed out.

When the pin 21^b is in the recess 3^b, the apertures 22 and 22^a are out of receiving position with respect to the heads 17^a and consequently the members 17 are held in engaging relation to the spindle 7; while the apertures 23 are in receiving position for the heads 18^a and the members 18 are there-

fore out of engaging relation to the spindle. During this time the spindle is held swivelly.

When the pin 21^b is in the recess 3^c, the apertures 22 are brought into receiving position for the heads 17^a and the apertures 23 and 23^a are out of receiving position for the heads 18^a, so that the members 18 engage the spindle.

The opposite, transverse body portions 5 are chambered cylindrically, and extending 75 outward, axially therethrough, are bearing or axle extensions 24 from the medial body portion 25; while the end of said body portion 25 affords a thrust bearing for the pinion 12.

Journalized with their hubs freely rotatable on the said axle extensions 24 are beveled gears 26, 26^a, respectively, which are constantly in mesh with said pinion 12; and on the outer faces of said gears 26, 26^a, are 85 annular series of clutch teeth 27, 27^a, respectively. Preferably, these teeth are provided on a separate disk 28 which is detachably secured to the gear, as by sleeving said disk on the hub of the gear and slotting the hub 90 to receive a fin or key projection on the disk. As shown, the hub is slotted diametrically, entirely across; and the disk has, of course, two of said fins or key projections diametrically opposed and fitting the slot 95 on opposite sides of the hub.

The clutch teeth 27, 27^a are segmental; that is, they are segments of an annular rib or collar on the outer face of the disk, and, therefore, each tooth presents a square 100 shoulder on opposite sides. This is to afford an engagement of the ratchet-pins, hereinafter described, to rotate the disk in opposite directions, as will be later more fully set forth.

Rotatable on the bearings or axle extensions 24, in abutting relation to the outer faces of the teeth 27, 27^a of the disks 28, are circular actuator or driving blocks 29, 29^a, said blocks being retained in place by 110 collars 30 on securing studs 31, which latter are inserted in axial bores in said axle extensions 24 and have a screw-threaded engagement therewith at their inner ends, as at 32.

Working in openings 33 in the driving block 29, is a pair of oppositely-arranged ratchet-pins 34, 34^a. That is, said pins have oppositely beveled heads 35, 35^a, respectively, at their inner ends, so that the disk 28 and 120 its subjoined gear 26 are rotated in either direction when the driving block is rotated, and according to which of said ratchet-pins may be in engaging relation to the clutch teeth 27 of the disk.

The ratchet-pins are normally pressed inward by springs 36, and they are selectively held out of operative relation to the clutch teeth 27, 27^a, by a contrivance as will be presently pointed out.

The opposite driving block 29^a is likewise provided with a similarly arranged pair of said ratchet-pins, but in reverse order to those on said block 29 (see Fig. 8). 5 Hence, when the pin 34 of the block 29, and the corresponding pin on the opposite block 29^a, are in operative engaging relation with respect to the teeth 27, 27^a, respectively, and said blocks are oscillated together, the gear 10 26 is rotated in one direction and the gear 26^a in the opposite direction; and the pinion 12, which is in mesh with both of said gears, is rotated correspondingly therewith in one and the same direction. That is, 15 on the one stroke of the driving blocks, the pin of the block 29 engages its companion toothed disk, thereby rotating the gear 26, and through it the pinion 12, which latter in turn drives the gear 26^a in the direction 20 opposite to that in which the gear 26 is moving; and during this time the teeth 27^a of the disk on said gear 26^a are riding over the beveled end portion of the ratchet-pin of the block 29^a. On the return stroke, 25 the ratchet-pin of the block 29^a engages the teeth of its companion toothed disk and the gear 26^a is thereby driven by said driving block 29^a in the same direction in which it was just previously driven by the 30 pinion 12; and during this time the gear 26 is, of course, being driven by the pinion 12 in the same direction in which it had been driven by its companion driving block 29.

To actuate the driving blocks 29, 29^a, they have the end portions 37, 37^a of the forks 38, 38^a of a bifurcated or substantially Y-shape operating handle or power lever 39 secured thereto. As shown, the 40 engagement of the members 38, 38^a with the respective driving blocks 29, 29^a, is effected by dovetailing the portions 37, 37^a of the handle 39 and fitting them into counterpart undercut grooves in said driving blocks and fastening them in place, as by screws 40.

Preferably, the stem portion of the handle or lever 39 is received normally in a groove 41 provided therefor in the handle or stock 1 of the device (see Fig. 1). This 50 is for the sake of compactness and as a guard for the handle stem when the device is not in use.

To simultaneously set the respective correlated ratchet-pins on both of the driving blocks 29, 29^a into and out of operative engaging relation to the respective clutch disks 28, semi-circular adjusting plates 42 are slidably mounted on the outer faces of said driving blocks, as by a slot-and-stud 60 connection 43 (see Fig. 1), and by providing cam slots 44, 45, in said plates, in which latter the ratchet-pins slidably engage, as will now be described.

Each of the ratchet-pins has a beveled 65 undercut head 46 which is freely movable

in the enlarged portion 47 of the cam slot, while the neck portion slidably fits the restricted portion of the slot.

By reversing the slots 44, 45, as shown in Fig. 1, and beveling the walls thereof, 70 where the restricted portions and enlargements merge, as at 48, the one of the ratchet-pins of the particular driving block is withdrawn from engagement with the teeth of the disk 28 when the adjusting plate is 75 moved to engage the neck of the pin with the restricted portion of its particular slot; while the other ratchet-pin has its head in the enlargement of its particular slot and is, therefore, in operative engaging relation to the teeth of the disk 28 (see Figs. 1 and 3). By moving the adjusting plate reversely, the relation of the ratchet-pins is, of course, reversed. Hence, the direction in which the spindle 7 is rotated is governed by the position of the adjusting plates 42. 80

In order to effect a simultaneous actuation of the adjusting plates 42, they are connected, as by a pivotal link connection 90 49, with the legs 50 of a substantially U-shape piece or yoke 51, which latter is slidably mounted on the handle 39 at about the junction of the stem and forks thereof, in some suitable manner, as at 52; and the device is provided with a suitable knob-like protuberance or grasping piece 53. By this means, the actuation of the adjusting plates 42 is effected by merely shifting the operating piece or yoke 51 longitudinally of 95 the handle 39, no matter in what position the latter may be; the movement of the adjusting plates 42 being limited by the slot-and-stud connection 43, and obviously by correspondingly limiting the movement at 100 the slidable connection 52 between the yoke 51 and handle 39.

In the head 8 of the spindle 7 may be provided a frusto-pyramidal socket 54, as shown, or, obviously, any suitable or approved chuck or fastening device, for the detachable engagement of various attachments or implements interchangeably, such as drill, screwdriver, or wrench-socket bits, or the lifting jack attachments hereinafter 115 described, when it is desired to use the device as a brace or lifting jack, as the case may be.

As shown in Figs. 1 and 2, a screwdriver bit 55 is in place; while in Fig. 7 there is 120 illustrated, detached, a jack-table or shelf 56 which has a swiveled shank 57 with interposed ball-bearings 58. In Fig. 6 a supporting base for the device when used as a lifting jack is shown as comprising a 125 flat plate 59 with an upstanding annular flange 60 constituting a socket for the reception of the end portion of the stock 1.

By the construction shown, a double-acting 130 ratchet effect is attained by oscillating

the operating handle or power lever 39 about the axis of the driving blocks 29, 29^a, while holding the stock 1 from rotation; and, as hereinbefore described, the spindle 7 is rotated either swivelly or with endwise movement, depending as to whether the clutch members 17 or 18 are in operative engagement with the spindle. So, too, in some cases where it may not be convenient to oscillate the handle 39 about the axis of the driving blocks 29, 29^a, it may be set at a right angle, or less, to the axis of the stock 1, and with it as a lever and oscillated about the axis of the stock 1, the device will, by reason of the arrangement of the correlated ratchet-pins which happen to be in engaging relation to the teeth of the disks 28, be rotated as a whole in one direction on the one stroke of the lever; while upon the opposite stroke of the lever, the spindle 7 will remain stationary, due to the slippage of the beveled end portions of the ratchet-pins over the teeth of the disks 28, the effect being that of a single-acting ratchet.

25 By using a swiveled table 56 of the character shown in Fig. 7, a substantial support is afforded the object to be lifted, and at the same time the shank 57 is permitted to rotate with the spindle 7, when the device is used as a lifting jack.

In some cases, where the device is used for drilling, and more particularly in heavy work, it is desirable to use in connection therewith a holding and feeding apparatus or harness. A preferred arrangement is shown in Figs. 9 and 10 of the accompanying drawings. As shown, the apparatus comprises a supporting bar 61 having a frusto-pyramidal projection 62 to fit a counterpart socket 63 provided therefor in the end of the stock 1. Preferably, this socket 63 is formed in a metal head 64 applied either with a collar or ferrule portion 65, as shown in Fig. 2; or with an elongated, tubular, axial extension 66 forming a lining for the bore 6^a, as shown in Fig. 10; and in which latter case, the end of the tube 66 may be secured to the body portion 3, as by screw-threaded or other suitable engagement.

50 The cross bar 61 is provided with an angularly disposed handle 67, which may be of the "pistol grip" type as shown, or otherwise, as desirable; while an axial socket 68 is provided within the projection 62 to receive the smooth end portion 69 of the feeding screw 70; the end of the screw being rounded and abutting the bottom of the socket 68.

60 A cross-bar 71 has a central, apertured enlargement or boss 72 which is screw-threaded to engage the threads of the screw 70. This cross-bar is provided with parallel guide rods 73 which slide through apertures provided therefor in the first-mentioned cross-bar 61, so that the two cross-bars are held

from independent rotative movement but are capable of endwise movement with respect to each other. Hence, by turning the screw 70, the bars 61 and 71 may be brought together or moved apart.

70 The ends of the cross-bar 71 are slotted, as at 74, or otherwise provided for the attachment of a chain or the like 75 after the latter is carried around the work to be drilled. As shown, the work comprises a pipe section 76, and a drill-bit 77 is placed in the socket 8 ready for the drilling operation. Obviously, by grasping the handle 67 and operating the lever 39, the drill is actuated through the mechanism hereinbefore described; and by rotating the screws 70, through the medium of the hand-wheel 78 provided thereon, the tool is fed toward the work. It is, of course, understood that the feeding screw is operated intermittently. 80 That is, the operator, after operating the lever 39 for a while to drive the bit 77, uses the same hand to manipulate the feeding screw 70, while still maintaining his hold on the handle 67 with his other hand.

85 Obviously, the device admits of considerable modification without in the least departing from the spirit of the invention. Therefore, it is not limited to the specific construction and arrangement shown in the drawings.

90 What is claimed is:

1. In a device of the character described, a spindle, ratchet driving mechanism for imparting rotation to said spindle and permitting endwise movement thereof, means engageable with said spindle for holding the same swivelly, and means for engaging said spindle to cause it to move endwise during rotation, the one of said means being ineffective when the other is effective.

100 2. In a device of the character described, a spindle, a pinion having an engagement with said spindle, whereby the latter is rotatable therewith but permitted endwise movement with respect thereto, means engageable with said spindle for holding the same swivelly, means for engaging said spindle to cause it to move endwise during rotation, the one of said means being ineffective when the other is effective.

110 3. In a device of the character described, a spindle, a pinion having an engagement with said spindle, whereby the latter is rotatable therewith but permitted endwise movement with respect thereto, means engageable with said spindle for holding the same swivelly, means for engaging said spindle to cause it to move endwise during rotation, the one of said means being ineffective when the other is effective, oppositely arranged gears engaging said pinion, whereby to rotate the latter in one and the same direction, oscillatory driving members for the respective gears, ratchet members on said driving members engageable with the respective gears, the one of said ratchet members being the reverse to the other on one of said driving members, and likewise on the other driving member but in reverse order, a lever for actuating said driving members together in either direction, and means for placing in engaging relation the one of said ratchet members on one of said driving members simultaneously with the

correlated ratchet member on the other driving member, and at the same time placing the other correlated ratchet members out of engaging relation, whereby to operate said 5 gears reversely in either direction.

3. In a device of the character described, a stock, a spindle, ratchet driving mechanism for imparting rotation to said spindle and permitting endwise movement thereof, 10 means for engaging said spindle to hold the same swivelly, means for engaging said spindle to cause it to move endwise during rotation, means for controlling said two mentioned means selectively, whereby the 15 one is effective while the other is ineffective, and means at the end of said spindle for the interchangeable attachment of implements of different character, whereby the device may be used either as a brace or a 20 lifting jack.

4. In a device of the character described, a stock, a detachable supporting base for said stock, a spindle rotatable in said stock and being also capable of endwise movement 25 with respect thereto, said spindle having means at its end for the interchangeable attachment of implements of different character, whereby the device may be used either as a brace or a lifting jack, a portion of said 30 spindle being screw-threaded, a clutch member having screw-threads corresponding to the screw-threads on said spindle, whereby, when in engagement therewith, said spindle is caused to move endwise during its rotation, a clutch member engageable with said 35 spindle to hold it swivelly, means for effecting the engagement of the respective clutch members selectively, and whereby the one member is ineffective when the other is effective, and reversible ratchet driving mechanism for imparting rotation to said spindle in either direction at will.

5. In a combined brace and lifting jack, a stock, a spindle rotatable therein and being 45 capable of endwise movement with respect thereto, a clutch member movable transversely in said stock, said spindle and clutch member being relatively arranged for engagement whereby the spindle is held 50 swivelly, a spring acting on said clutch member to normally move the same out of engagement with said spindle, a second clutch member likewise movable in said stock for engagement with said spindle and 55 being relatively arranged therewith to cause it to move endwise when rotated, and a sleeve rotatable on said stock and having openings to receive the outer end portions of said clutch members, the opening for the one 60 clutch member being in a different diametrical direction from that for the other clutch member, the edges of said openings and corresponding edges of said clutch members being correspondingly cam-shaped, whereby, 65 when said sleeve is turned to take the open-

ings out of receiving position said clutch members are respectively forced inward into engaging relation with said spindle.

6. In a device of the character described, a driving pinion, oppositely arranged gears 70 engaging said pinion whereby the said gears rotate in opposite directions when the pinion rotates in either direction, an annular series of clutch teeth on said gears, oscillatory driving members for the respective 75 gears, said driving members being rotatable together in either direction, pairs of reversed, spring-pressed, beveled ended ratchet-pins on said driving members for engagement with said clutch teeth, the one 80 of said pins of each pair being made to drive the companion gear in one direction, and the other pin to drive the same in the opposite direction, and the pair of ratchet-pins on the other driving member being ar- 85 ranged in reverse order, whereby said gears are rotated in reverse direction, said ratchet-pins having stem portions with tapered undercut heads at their outer ends, adjusting plates slidable on said driving members and 90 having cam slots, said slots having restricted portions to which the stems of said ratchet-pins are slidably fitted and enlargements to which the heads of said pins are likewise fitted, the walls of said slots where the re- 95 stricted portions and enlargements thereof merge being cam-shaped, and the cam slot for the one pin being reversed with respect to the other, whereby, when the one ratchet-pin on the driving member is in engaging 100 relation to the clutch teeth of the companion gear the other pin of the pair is held out of such relation, and means for simultaneously actuating said adjusting plates.

7. In a device of the character described, 105 a spindle, ratchet driving mechanism for imparting rotation to said spindle and permitting endwise movement thereof, a clutch device for engaging said spindle to hold the same swivelly, a clutch device for engaging 110 said spindle to cause it to move endwise during rotation, and a controlling device for said clutch devices, said controlling device being operable to effect the release of both of said clutch devices simultaneously from 115 said spindle, and also to render the one clutch device effective while the other is ineffective.

8. In a device of the character described, 120 a spindle, driving mechanism for imparting rotation to said spindle and permitting endwise movement thereof, said spindle having means for engagement of a clutch member to hold it swivelly, and having a screw-threaded portion for engagement of a clutch member to give it endwise movement during rotation, a clutch member for the said swivel engagement, a clutch member for engagement with the said screw-threaded portion of the spindle, and a controlling device for 125 130

said clutch members, said controlling device being operable to effect the simultaneous disengagement of said two mentioned clutch members, and also for rendering the 5 one member ineffective while the other is effective.

9. In a device of the character described, a stock having a socket in its end, and a holding and feeding attachment, the latter 10 having a supporting member provided with a portion to rigidly but detachably engage in said socket of the stock, and also having a gripping handle, a second member 15 capable of longitudinal movement only with respect to said supporting member, and having means for attachment to the work, and a feeding screw working through said second-mentioned member and bearing endwise on said supporting member. 20

10. In a device of the character described, a stock having a non-circular socket in its end, and a holding and feeding attachment, the latter comprising a supporting bar having a counterpart extension to rigidly but 25 detachably fit said socket of the stock, and also having a gripping handle, a second bar having guide rods slidable through apertures provided therefor in said supporting bar, and having provision at its ends for 30 engagement of a work attaching element, and a feeding screw working through said second-mentioned bar, axially with respect to said stock, and bearing endwise in a socket provided therefor in said first-mentioned supporting bar. 35

Signed at St. Louis, Missouri, this 9th day of August, 1918.

THOMAS J. McADAMS.
